[57] CLAIM

The ornamental design for a telescopic walking stick, as shown and described.

DESCRIPTION

FIG. 1 is a side elevational view of a telescopic walking stick showing my new design, in closed position, the other side view being a mirror copy of this one; FIG. 2 is a front elevational view thereof, in closed position;

FIG. 3 is a top plan view thereof;

FIG. 4 is a side elevational view thereof, in open position, the other side view being a mirror copy of this one; FIG. 5 is a front elevational view thereof, in open position;

FIG. 6 is a rear elevational view thereof, in closed position;

FIG. 7 is a rear elevational view thereof, in open position; and,

FIG. 8 is a bottom plan view thereof.

FIG. 1
